(57) **CLAIM**

We claim the ornamental design for an information handling system docking station, as shown and described.

DESCRIPTION

FIG. 1 is a front perspective view of the information handling system docking station with an information handling system shown mounted to the docking station comprising the present invention;

FIG. 2 is a front perspective view thereof;

FIG. 3 is a front view thereof;

FIG. 4 is a right side view thereof;

FIG. 5 is a left side view thereof;

FIG. 6 is a back view thereof;

FIG. 7 is a top view thereof; and,

FIG. 8 is a bottom view thereof.

Broken lines shown in the drawings illustrate portions of the information handling system docking station, and form no part of the claimed design.
